UNITED STATES PATENT OFFICE.

JACOB M. ROBERTS, OF NORFOLK, VIRGINIA.

ELECTRIC-SPARK-GAP APPARATUS.

1,188,324.

Specification of Letters Patent. Patented June 20, 1916.

Application filed November 4, 1914. Serial No. 870,239.

To all whom it may concern:

Be it known that I, JACOB M. ROBERTS, a citizen of the United States, residing at Norfolk, in the county of Norfolk and State 5 of Virginia, have invented certain new and useful Improvements in Electric-Spark-Gap Apparatus, of which the following is a specification.

My invention relates to spark gap apparatus for transmitting electric waves in 10 wireless telegraphy and telephony.

The object of the invention is to provide a sending device using an electric spark gap whereby a flow of air is mingled with the 15 spark to produce a cooling effect thereupon and preventing variations of the intensity of the signals sent out and thereby eliminating the over heating effect of the spark gap.

Further objects and advantages will be 20 more fully described herein and specifically pointed out in the annexed claims recourse being had to the accompanying drawings in forming a part of this specification in 25 which:

Figure 1 is a front view of the complete apparatus. Fig. 2 is an end view and a cross section through the base board in the direction of the line 1-2 in Fig. 1. Fig. 3 30 is a side view of the air blast chamber showing a single orifice therethrough. Fig. 4 is a side view of the chamber showing a series of holes through the same. Fig. 5 is an edge view of the blast chamber or box. Fig. 35 6 is a front view of one of the plates or disks forming a part of the blast chamber and shows a removable perforated disk or center therein. Fig. 7 is an edge view of the same. Fig. 8 is a part side elevation and 40 section of one of the spark gap terminals or points and its support. Fig. 9 is an end view of one of the spark gap points or terminals showing multiple channels through the same. Fig. 10 is an end view of one of 45 the terminals showing a single channel therethrough. Fig. 11 shows a multiple arrangement of the blast chambers when placed in series with each other. Fig. 12 is an end view of the same partly in section 50 showing adjusting means for the chambers. Fig. 13 is a sectional view of a modified form of spark point, and Fig. 14 is an enlarged fragmentary portion in section, of one of the spark points showing the action 55 of the air blast and spark.

In the drawings like reference numerals

indicate similar parts in all the several views.

1 is the base board or support for the hereinafter described devices and is provided with legs or standards 2 so that the base 60 may be elevated forming a space beneath the same.

3, 4 and 5 are supports or blocks which act also as insulators for the hereinafter 65 named metal devices.

6, 6 are grooved plates mounted upon the blocks 3 and 5 and are connected by the rods 7 to the terminals or binding post nuts 8, the rods 7 passing through the blocks and the base board 1, as shown. The terminals, 70 as at 8, are the connection for the power electric circuit.

9 are slidably mounted plates provided with a dovetail connection working in a 75 corresponding groove or channel in the plates 6, and are provided, also, with an offset portion 11 so that the operating rod 12 may be out of the way of the hereinafter 80 described piping. The rods are threaded and pass through the ends of the muffler 85 casing to the outside thereof, and are provided with thumb nuts 13 for convenience in operating the plates 9. By either turning the rods 12 inward or outward the plates 85 may be moved so as to adjust the herein- 90 after described spark points and when they are at the proper distance apart, the rods may be locked by means of the jam nuts 14.

15 is a muffler casing or inclosure for the 95 described mechanism and is composed of some suitable insulating material and adapted for reducing the noise of the spark and for protection against heat and sparks for such use I employ an asbestos lining 16. The 95 muffler casing is provided with a glass door 16^a, Fig. 2, so that the internal mechanism may be reached and observed.

17 is an air outlet or monitor on top of the casing 15 and is provided with outlet holes 100 or orifices 18 for the escape of heated air which may be drawn out by a suitable exhaust fan. The dome or monitor may be extended to any height that may be desired.

18^a are holes in the top of the casing 15 105 to allow heated air within the same to be expelled through the dome 17.

19 are metal blocks secured to the dove- 110 tailed plates 9 and may be square in cross section, as in Fig. 1, or cylindrical as in Fig. 8. The blocks or cylinders are tapped to receive the screw 20, (dotted lines), upon

the portion 21 of the spark points 22. The spark points or gap terminals, are provided with a single perforation 23, for a flow of air to mingle with the spark, or a series of perforations or orifices, which will be described hereafter.

24 is an annulus or ring, and said annulus, taken with the circular plates or disks 25, form an air blast chamber or box, said 10 disks being secured to the annulus by the screws 26.

27 is an air inlet pipe and 28 an air outlet pipe, the latter being smaller than the inlet, permits of a pressure being maintained within the chamber but still permitting a flow or movement of air as it will not escape as rapidly as it enters. In addition to the outlet 28, the blast chamber is provided with a single aperture or blast outlet 29, in Figs. 3 and 12, or a series of the same arranged in concentric rows, as at 30 15 in Figs. 4 and 6. Instead of perforating the disks, as in Fig. 4, I arrange a center 31 provided with a flange 32, and in this manner I may renew the center, if required, by placing a suitable wrench in the holes 33, Fig. 6, and unscrewing the center from the disks. The blast chamber may be extended to any length, as shown by the dotted lines 30 20 34, Fig. 5.

I may place a number of air chambers in series with their renewable spark points 34^a, Fig. 13, opposite to each other, as shown in Fig. 11 and which will now be described.

35 Referring to Figs. 11 and 12, 35 are blocks of suitable non-conducting substance and act as supports for the chambers 25. The blocks are slidably mounted upon the rod 36 and held thereon at any distance apart, by the 40 set screws 37. Air is supplied to the blast chambers through the channel 37^a which is connected to a suitable blast device by means of the flexible rubber tubes 38. Upon the edge of the blast chamber is placed a 45 scale 39 as a guide for adjusting the distance between the spark points and it is numbered from its center to both ends. 40 is a deflecting disk mounted upon the spark points 22 by means of the screw thread 41 and is for the purpose of allowing the air blast to be deflected from the blast chamber disks 25, thereby causing air currents around the spark gap. The combined spark points and air jets 22 are provided with either a 50 single longitudinal channel 23, Fig. 10, or a series of orifices 42, as shown in Fig. 9.

Referring to Fig. 14, 43 represents a 55 discharge of electric sparks from an opposite point and directed into the counter-sunk or bevel portion 44, of the spark point, where they meet the air discharging from the opposite direction through the passages 23 and consequently blown with and into the sparks. In this manner the spark is 60 rendered steady and cool and the air blast

is regulated according to the intensity of the spark desired. 45, Figs. 1 and 2, represents the main blast inlet pipe supplying the vertical branches 46 and by means of the elbows 47 the pipe is made to supply 70 the air to the parts 21 of the points 22 by rubber tubes 48 so as to have a flexible connection when the points are adjusted for regulating the air gap or spark gap. 49 are suitable valves in the pipes 46 for controlling the air supply to the spark points. 50 is a cylinder adapted to be filled with some moisture absorbing substance for drying the air before it reaches the spark gap points, and 51 is a pipe leading to a suitable air supply. In ordinary spark gaps where a fan or blower is used it is disadvantageous, as it makes the spark waver and be blown, to a certain extent, out of its course. In my device I supply a flow under a certain pressure thereby cooling the disks 25 of the air chamber, the points 22 and the spark itself, besides driving out heated air surrounding the spark gap and keeping the spark at a minimum working temperature. 90

With my invention, I can produce and maintain a better all around spark than is possible with other spark gaps. A rotary gap must be stopped before making adjustments, but in my apparatus, adjustments 95 may be made without stopping any part of the device.

My invention displaces some of the parts necessary in the operation of other spark gaps now in use besides giving a steady 100 spark and a perfect cooling effect thereby causing high radiation.

I claim:—

1. A device of the class described comprising sparking points having openings 105 therein, means for causing air to flow outward through said openings, a chamber between said sparking points having openings through the opposite walls thereof, and means for causing air under pressure to pass therethrough.

2. A device of the class described comprising air pressure means, adjustable spark and air discharging points, and a means between said points having air pressure regulating means, said air pressure means being operatively connected with said points and said means therebetween. 115

3. A device of the class described comprising air jet spark points, an adjustable apertured chamber between said points having an unrestricted inlet and a restricted outlet, and deflecting or reflux disks on said points. 120

4. A device of the class described comprising movable channeled air and spark discharging points, an apertured air retarding chamber therebetween and means for causing air to pass outward through the apertures in the opposite walls thereof 125 130

under pressure and means for regulating said pressure.

5. A device of the class described comprising air pressure means, combined uni-directional air and electric spark dischargers, an air flow regulating and discharging means between said dischargers, and air deflecting disks on the dischargers, said air pressure means being operatively 10 connected with said discharge and said means therebetween.

6. A device of the class described comprising adjustable combined air blasts and electric spark terminals or points, a chamber 15 between said points having apertured walls, means for maintaining air under pressure therein and for forcing it through said aper-

tures, and a scale on said chamber adapted to be a guide for adjusting the distance between said points.

20

7. A device of the class described comprising air blasts and spark discharging points, deflecting disks or shields thereon, an apertured chamber at the meeting point of the air discharges, means for forcing air 25 under pressure through said apertures, and drying means for the air.

In testimony whereof I have hereunto affixed my signature in the presence of two witnesses.

JACOB M. ROBERTS.
